United States Patent Office

Des. 182,220
Patented Mar. 4, 1958

182,220

SPOON OR THE LIKE

Bernie B. Berry, Jr., Indianapolis, Ind.

Application April 26, 1956, Serial No. 41,213

Term of patent 14 years

(Cl. D54—12)

FIG. 3

Fig. 1 is a front view of a spoon showing my new design.

Fig. 2 is a side view thereof.

Fig. 3 is a sectional view taken on line 3—3 of Fig. 1.

Fig. 4 is a sectional view taken on line 4—4 of Fig. 1.

Fig. 5 is a fragmentary rear view thereof.

I claim:

The ornamental design for a spoon or the like, as shown.
